UNITED STATES PATENT OFFICE.

JOHN H. ASHTON, OF PROVIDENCE, RHODE ISLAND.

WATER-HEATER.

1,132,757.

Specification of Letters Patent. Patented Mar. 23, 1915.

Application filed September 23, 1914. Serial No. 863,074.

To all whom it may concern:

Be it known that I, JOHN H. ASHTON, a citizen of the United States, residing at Providence, in the county of Providence and State of Rhode Island, have invented 5 certain new and useful Improvements in Water-Heaters, of which the following is a specification.

My invention relates to an improved 10 heating appliance or apparatus for use in shower bathing, and it consists in the construction and arrangement of parts substantially as hereinafter set forth and claimed.

15 In the accompanying drawing Figure 1 is a side elevation, in partial section, showing my improved shower bathing appliance complete; Fig. 2 is a corresponding top plan view; and Fig. 3 is an enlarged vertical 20 sectional view taken through the lower portion of the steam inlet connection.

A, in the drawings indicates a shower bath device embodying my improvements. The lower cap B consists of the disk-like horizontal head provided with an integral projecting bracket α^2 having a vertically disposed flange α^3 adapted to be secured by bolts m^1 to a support or partition, as p ; the said head is further provided with suitably 25 located small hubs or bosses f^1 , c^3 and c^4 , tapped to respectively receive the inlet branch pipe f of the cold water main 1; the inlet branch c leading from the live steam main 2, and the outlet branch e leading to 30 the waste or exhaust main 3, which conducts the condensed steam from the heating coil D. The water heating tank a consists of a hollow cylindrical metal casing having its lower end provided with an outer flange α^1 35 registering with said head B, the tank being removably secured to the head by means of bolts m and forming a water tight joint. The upper end of the tank has an open cylindrical recess of considerable depth formed 40 therein; the bottom of the recess being closed. A steam heating coil D is located and secured in the tank a ; the inlet member c^1 of the coil is shown as extending upwardly 45 from the boss c^3 and between the adjacent wall of said recess b and the inner periphery of the convolutions of the coils of the heater; the outlet member c^2 of the coil terminates at the lower end in the boss c^4 and is mounted water tight therein in substantially the 50 same way as the inlet c^1 is mounted. That is to say, the tubular boss c^3 (Fig. 3) is re-

cessed to receive a suitable packing ring p^1 on which is superposed the circular flange p of the connection c^1 ; a screw threaded nut or gland r engageable with the boss serves to 60 connect the members snugly together.

A boss n is tapped to receive a suitably bent tube n^1 , the latter communicating with the tank's interior at or near its upper end. To the outer end of the tube n^1 is removably 65 secured a shower head E, said head element being provided with a number of fine holes or perforations arranged for discharging water therefrom in the form of spray, shower, etc. It will be seen that the direct 70 admission into the tank of cold water under pressure from the main 1 is controlled by a manually actuated valve v , while the valve v^1 performs a similar office for the admission of steam from the main 2 into the heating coil; and the exhaust or condensed steam 75 from the coil flows into the exhaust main 3 via an interposed normally open check-valve v^2 . The check valve is employed solely to prevent a possible back-flow of vapor or water 80 of condensation into the coil in case an accumulation of vapor or water under pressure in the main 3 might occur, the back pressure then causing the valve to close or seat itself on the upper side; the steam inlet 85 valve v^1 to the coil D obviously being closed.

The normal operation of the device is substantially as follows: Assuming the water inlet valve v to be open and the tank thereby filled or charged with water from 90 the main 1, the user next opens the steam valve v^1 communicating with the main 2 and the immersed coil D; the pressure of the steam acts to quickly increase the temperature of the water, the rise in temperature being relatively greater in the upper portion of the tank owing to the lesser volume of water at that point caused by the displacement due to the presence of the inner recess b . The volume of water and rate of its flow 95 from the shower head E is or may be controlled by manipulating the valve v . It may be stated that the aggregate area of the perforations formed in the head E is somewhat less than the area of the water inlet tube f , therefore the water is adapted to issue from the head with an accelerated force, it being understood that the water from the pipe f enters the tank a under pressure. By means of a suitable cock, as h , 100 the tank may be first emptied of water, in case it is desired to inspect the interior of 105

the heater for any purpose, followed by simply removing the bolts m and taking off the tank; the heating coil meanwhile remains intact and normally secured to the 5 bottom cap or flange B. It may be added that a battery of individual heaters or units 10 embodying my improvements may be located at suitable intervals from one another and connected to mains common to all. As thus arranged any or all of the heaters are capable of being utilized at the same time as desired. By closing the steam valve v^1 and opening the cold water valve v a person may receive a cold shower bath. By 15 opening both the said valves, $v v^1$, a hot or warm shower is secured. By closing valve v and opening valve v^1 the water in the tank will be gradually converted into low pressure steam or vapor, to produce a vapor 20 bath, and after a warm shower the valve v^1 may be closed and the water inlet open thereby gradually cooling the temperature of the shower until the temperature of the water issuing from the head E is the same as that 25 of the inflow from the pipe f.

In my improved shower bathing appliance the construction is simple, easily operated, comparatively inexpensive to manufacture and not liable to become accidentally inoperative. It possesses the added advantages of heating the water more quickly owing partly to the inclosed displacement member b fixed interiorly of the tank chamber. The device A differs from other shower 30 heaters of this general type in that the latter includes the use in each of a thermostat, a diaphragm valve, a thermometer, and also requires the services of a skilled attendant.

40 I claim as my invention:—

1. A water-heating apparatus comprising a flat, disk-like bottom head, said head having means integral therewith for securing the apparatus to a side wall, a steam heating 45 pipe coil secured to and extending upwardly from said head, said coil adapted to connect respectively with a steam supply and exhaust, means for automatically preventing back-flow of vapor or water of condensation 50 into the coil, an inverted hollow cylindrical casing or water tank, said tank fixed water-tight to the upper side of said head

and completely enveloping the heating-coil, means connected with said head for supplying water under pressure into the tank to be 55 heated therein by the coil, and means for discharging water from the tank, constructed and arranged whereby the tank is adapted for removal bodily from the bottom head, while all the pipe-joints are intact, thereby 60 rendering the heating-coil easily accessible.

2. In a water heating apparatus of the general character described, the combination of a relatively stationary base head, a steam heating coil secured to said head, a chambered tank or casing enveloping said coil removably secured to the base, the upper portion of said casing being provided interiorly with a fixed longitudinally extending displacement member arranged to reduce the 65 area of the water space at that point to facilitate heating, and having coils of the heater circularly disposed in the space lying between the wall of the said displacement member and the inner surface of the wall 70 of the casing.

3. In a heating device for individual or unitary shower bathing apparatus, a bottom or base flange, said flange having an extension or bracket integral therewith 80 adapted to be secured to a wall or support, a tank for holding water removably secured to said base flange, a steam heating coil having its ends secured in said flange and extending upward in the tank, controlled means for admitting steam under pressure to the heating coil, an automatically operable check valve connected with the exhaust end of the coil to prevent a back 85 flow of condensed steam, vapor, &c., under 90 pressure from entering the coil, and controlled means for admitting water under pressure into the tank and around the heating coil from a source of supply, the said tank being adapted for removal bodily from 95 the said base flange, the latter at the same time having the coil and its connections normally connected therewith.

In testimony whereof I have affixed my signature in presence of two witnesses.

JOHN H. ASHTON.
